CONICAL PAPER CUP

Frederick T. Krein and Torris H. Alfreds, Park Ridge, Ill., assignors, by direct and mesne assignments, to Dixie-Vortex Company, Chicago, Ill., a corporation of Delaware

Application September 30, 1935, Serial No. 42,768
Renewed December 20, 1937

10 Claims. (CL. 229—1.5)

This invention relates to improvements in conical paper cups and it consists of the matters hereinafter described and more particularly pointed out in the appended claims.

5 The cups with which the present invention is more particularly concerned, are of the kind in which a measured quantity of ice cream or other frozen or semi-solid confection is delivered to the retailer for future sales to customers, and which 10 cups are removed from the ice cream or other frozen or semi-solid confection previous to its placement in an edible cone, service dish or glass, for the customer.

One of the objects of the present invention is 15 to provide a cup of this kind having means for separably securing the overlapping side wall margins of the cup together in a manner permitting a quick and easy stripping or unrolling removal of the cup from its contents for placing the latter in an edible cone or other serving container.

A further object of the invention is to provide 20 a cup of this kind having separably secured overlapping side wall parts, one of which includes a relatively free tearing tab extending the full height of the cup whereby the cup may be unrolled from its contents without danger of merely tearing away of a part of the cup with the resulting unsanitary engagement of the hands of the operator with said contents.

30 Another object of the invention is to provide a cup of this kind with a tab at the top of the cup, above the contents thereof and by which tab the cup may be held by one hand while the other is employed in stripping the cup from its contents 35 for insertion in an edible cone or in a serving dish or the like.

Still another object of the invention is to provide 40 in a cup of this kind, a novel slit and tongue arrangement for separably securing the overlapping side wall parts together, without the aid of adhesives and in a manner permitting the use of a tearing tab extending the full height of the cup for a quick stripping of the same from its contents 45 for serving.

Again, it is an object of the invention to provide 50 a cup of this kind which may be produced from a blank of paper substantially of an elliptical lanceolate form, which when rolled into cup form, provides a relatively tight apex end structure therefor.

The above mentioned objects of the invention, as well as others, together with the several advantages thereof, will more fully appear as we proceed with our specification.

55 In the drawing:

Fig. 1 is a perspective view of a conical paper cup embodying the preferred form of the invention.

Fig. 2 is a plan view of a blank from which the cup shown in Fig. 1 may be made.

Referring now in detail to that embodiment of the invention illustrated in the accompanying drawing, 5 indicates as a whole the blank from which the cup is formed. As shown in Fig. 2 herein, said blank, which is made of a paper suitable for the purpose, is substantially of an elliptical lanceolate shape instead of being quadrantal or segmental as in the conventional practice.

Said blank has curved top and bottom edges 6 and 7 which meet at the ends of the blank as substantially pointed corners 8 and 9 respectively.

The edge 7 includes edge portions 10 and 11 respectively, the inner ends of which terminate as opposite curve portions 12 and 13 which meet at a point 14 located in about the transverse median line of the blank. The curve portions 12 and 13 define lips 15 and 16 respectively on opposite sides of a recess 17, the inner end of which reaches the point 14 and which point approximately forms the axis or center for the curved top edge 6.

In that margin 18 of the blank as defined by the edge portion 11 and spaced inwardly a suitable distance therefrom, is a slit 19 and in that margin 20 of the blank as defined by the edge portion 10 is a tongue 21 formed by a slit 22. The tongue and slit are so arranged in their respective margins that the end 23 of the slit 19 is a slight distance further from the point 14 than the end 24 of the tongue-defining slit 22, when said distances are measured on the lines A and B respectively in Fig. 2.

Adjacent the end 8 of the blank and projecting outwardly from the curved edge 6 thereof is a tab 25, the purpose of which will presently appear.

In the folding of the blank into cup form, and which may be carried out either by hand or by machine, the margins 20 and 18 are brought into overlapping relation, with the margin 20 on the inside of the cup and with the margin 18 on the outside of the cup as shown in Fig. 1, the tongue 21 in this operation being inserted through the slit 19. When the parts mentioned are in proper position, the end 24 of the slit 22 engages the end 23 of the slit 19 is separably secure the overlapping margins together so as to hold the blank in cup form.

As before mentioned, the distance between the point 14 and slit end 23 is a trifle greater

than the distance between the point 14 and the slit end 24. Due to this difference, when the blank is in cup form, the outer side wall margin 18 tends to exert a slight upward lift on the inner side wall margin so as to tension the margin 20 in the direction of its length. This will cause the lip 15 to wind or curl outward against the lip 16 with the result that the cup is tightly closed at its apex and as provided by the point 14. This action will also cause the margin 20 to more tightly hug against that part of the cup blank which it underlaps. The margin 18 outwardly beyond the tongue and slit, forms a tab for gripping by the fingers of the hand in stripping or unrolling the cup from its contents. In this respect it is pointed out that as the cup is especially intended for use in connection with ice cream or similar products, as before mentioned, it is not necessary that the overlapping engagement between the outer and inner side wall margins be water tight.

If desired, the blank may be rolled in the opposite direction to bring the margin 20 on the outside of the cup and the margin 18 on the inside of the cup, the margin 20 then functioning as the full-length tearing tab. This, of course, would bring the tongue 21 on the inside of the cup instead of on the outside of the cup as shown in Fig. 1.

Assume that the cup, as shown in Fig. 1, contains a quantity of ice cream and it is desired to serve the ice cream to a purchaser as in an edible cone. Holding tab 25 between the fingers of one hand, the margin 18 is grasped by the fingers of the other hand and is turned over and unrolled in the direction of the edge 10 of the other margin, thus separating the two margins. When the cup is peeled or stripped from its contents, the latter is permitted to drop into an edible cone. In this separation, the tongue will either slip through the slit or break off. If the contents are to be served in a dish, the cup is held, base or mouth end down and the cup is stripped or unrolled from the ice cream in the manner above mentioned. Thus, in handling the cup in serving the contents thereof, either for use in an edible cone or in a dish, no portion of the hands or fingers of the operator comes in contact with the contents. Therefore, the serving of the contents is indeed sanitary.

Cups made in accordance with the present invention, may be easily produced by machine and nest with each other in a manner which prevents them adhering together, as the tongue 21 and margin or tearing tab act as spacers. Also as the tearing tab extends the full height of the cap, and as the tongue and slit separably connect the overlapping side wall parts, at about midway between the top and bottom ends of the cup, the tab or margin will not tear but will insure a clean stripping of the cup from its contents in the least possible time.

In describing the invention, we have referred in detail to the form, arrangement and construction of the cup blank, as well as to the manner in which it is rolled into cup form, the same is to be considered only in the illustrative sense so that we do not wish to be limited thereto except as may be specifically set forth in the appended claims.

We claim as our invention:—

1. A conical paper cup made from a blank having an edge defining the mouth of the cup and having inner and outer overlapping side

wall parts each defined by a curved edge and extending from said mouth to the closed apex end of the cup, the curves of said edges being away from each other, means devoid of adhesive for separably securing portions of said side wall parts together at a point between said curved edges, the margin of the outer wall part between its edge and said means forming a tearing tab, at least in part, for use in separating said side wall parts in opening the cup, said means devoid of adhesive being so spaced from the closed apex end of the cup as to tension one of said wall parts longitudinally to cause the margin of the inner wall part between its edge and said means, to have a yielding engagement against the outer side wall part.

2. A conical paper cup made from a blank having an edge defining the mouth of the cup and having inner and outer overlapping side wall parts extending from said mouth to the closed apex end of the cup, one of said side wall parts having a slit therein arranged at an angle and spaced inwardly from the edge of said one of said wall parts, the other of said wall parts having a hook-like tongue therein spaced from the edge of said other wall part and engaged in said slit, said slit and tongue being so relatively spaced from the closed apex end of the cup as to tension one of said wall parts longitudinally to cause said hook-like tongue to engage in the slit with a tighter locking action and to cause that part of said other wall part between its tongue and edge to engage with a yielding action against the associated surface of the first-mentioned wall part.

3. A paper cup blank of approximately an elliptical lanceolate shape and having one margin defined by an arcuate edge and having a second margin defined by two substantially outwardly and oppositely curved edges, each of which terminates at the inner end in a curve of less than 90° in extent and of a lesser radius than that of the remainder of said curved edges and which curves of lesser radii meet at a point approximating the center for the first-mentioned edge.

4. A paper cup blank of approximately an elliptical lanceolate shape and having one margin defined by an arcuate edge and having another margin defined by two substantially outwardly and oppositely curved edges each of which terminates at the inner end in a curve of less than 90° in extent and of a lesser radius than that of the remainder of said curved edge and which curves of lesser radii meet at a point approximating the center of the first-mentioned edge, there being a slit in one part of said second margin and a tongue with a hook in another part of said second margin for engagement in the slit to separably hold the blank in cup form.

5. A paper cup blank of approximately an elliptical lanceolate shape and having one margin defined by an arcuate edge and having a second margin defined by two substantially oppositely curved edges each of which terminates at the inner end in a curve of a lesser radius than that of the remainder of said curved edge and which curves of lesser radii meet at a point approximating the center of the first-mentioned edge, there being a slit in one part of said second margin defining a tongue and there being a second slit in another part of said second margin to receive said tongue to separably hold the blank in cup form, one end of said second-mentioned slit being spaced from said point a distance different from the distance between said point and the associated end of the first-mentioned slit.

6. A paper cup blank of a general elliptical lanceolate shape and having two substantially oppositely curved edges, one of said edges having a pointed recess therein, the point of said recess forming substantially the center for the curvature of the other edge, and a tab projecting from said other edge at a point spaced from one end of said edge.

7. A paper cup blank of a generally elliptical lanceolate shape having two substantially oppositely curved edges arranged upon opposite sides of a line extending through the ends of the blank, one of said edges having a pointed recess therein which is substantially coincident with the center of curvature for the other edge and which center is spaced laterally from said line toward the edge with the recess therein.

8. A blank for a conical paper cup having two substantially pointed end portions and a curved edge to one side of a line extending through said pointed end portions to form the mouth of the cup and having other edge portions to the other side of said line and disposed other than parallel therewith to form the overlapping side wall parts of the cup, there being a portion projecting from one point on said curved edge to form a tab for holding the cup.

9. As an article of manufacture, a conical-like cup for receiving and having frozen therein an edible confection such as ice cream comprising a

paper blank rolled into conical form with overlapped margins and having interlocked portions for temporarily holding the margins together throughout their length until ice cream is frozen therein and being readily separable upon the peeling of one of the margins off of the frozen mass to remove the cup therefrom, one of said overlapped margins projecting beyond said interlocked portions for forming a tearing tab which extends substantially from the mouth of the cup to its lower end.

10. As an article of manufacture, a conical-like cup for receiving and having frozen therein an edible confection such as ice cream comprising a paper blank rolled into conical form with overlapped margins and having interlocked portions for temporarily holding the margins together throughout their length until ice cream is frozen therein and being readily separable upon the peeling of one of the margins off of the frozen mass to remove the cup therefrom, said interlocked portions being so constructed and arranged with respect to said overlapped margins as to leave a part of one of the margins free so that it may serve as a stripping tab in the peeling of the cup off of the frozen mass and which stripping tab extends substantially from the mouth of the cup to its lower end.
